PRODUCTION OF VALUABLE HYDROCARBONS FROM GASEOUS HYDROCARBONS

Fritz Winkler and Hans Haeuber, Ludwigshafen-on-the-Rhine, Germany, assignors to I. G. Farbenindustrie Aktiengesellschaft, Frankfort-on-the-Main, Germany

No Drawing. Application March 16, 1931, Serial No. 523,183. In Germany March 22, 1930

1 Claim. (Cl. 260—168)

The present invention relates to the production of valuable hydrocarbons from gaseous hydrocarbons of the paraffinic and olefinic series.

We have found that the conversion of normally gaseous saturated or olefinic hydrocarbons, as for example methane, ethane, ethylene and the like, if desired in admixture with other gases, such as nitrogen or hydrogen, into hydrocarbons of higher molecular weight, especially into liquid hydrocarbons of aliphatic and aromatic nature, by heating the gases to high temperatures between 400° and 1100° C. is effected with particular advantage, if these gaseous hydrocarbons are first laden with metal vapors at a temperature which lies above the melting point and, if desired, above the boiling point of the metal employed but below the said conversion temperature of the said gases and then heated in the presence of the said metal vapors to the said conversion temperature. Metals which come into question for the present process are in particular those which melt below 500° C., such as mercury, cadmium, lead, tin or zinc.

The gases may be laden with metal vapors by being passed through molten or boiling metals, by being passed over molten or boiling metals or by injecting into them vapors of metals or gases, for example diluent or indifferent gases, such as nitrogen or hydrogen, containing said vapors.

The vapors of the metals are usually added to the gases to be treated or under treatment in small amounts, for example in an amount of about up to 2 per cent of the volume of the said gases, but also greater amounts of metal vapors may be added though the effect obtained is not substantially increased thereby. There exists no under limit of the amounts of metal vapors to be employed since even traces as for example 0.01 per cent of the said vapors have a remarkably favorable effect on the treated gases.

The mixtures containing the metal vapors may also be led over catalysts, such as those used in pyrogenic reactions, as for example over silicon, molybdenum, tungsten, chromium or carbon in various forms such as graphite, coke and the like, the heat necessary for the reaction being supplied by the catalysts if desired, instead of through the walls, by employing them as electrical resistances. Such catalysts are advantageously employed as do not give rise to a deposition of carbon. By working thus with solid catalysts, inter alia, a better utilization of the heat is ensured. The walls of the reaction chamber are preferably constructed of or coated with a material which prevents the deposition of car-

bon, as for example chromium, graphite, tin, tin alloys, as for example with lead, and the like. The process according to the present invention may be carried out at any pressure under which at the temperature employed the vapor pressure of the metal used is so high that the metal vapor may be present in an amount of 0.01 per cent of the hydrocarbon gases treated. The reaction temperature is generally speaking between 400° and 1100° C., and advantageously above about 500° C. but varies according to the hydrocarbons to be converted and to the other working conditions. At temperatures below from 700° to 750° C. mainly aliphatic hydrocarbons are obtained, whereas above this interval the formation of aromatic hydrocarbons predominates.

In general, the higher the number of carbon atoms in the molecule, of the initial gaseous hydrocarbons, the lower will be the temperature required.

The following examples will further illustrate the nature of this invention, but the invention is not restricted to these examples. The percentages are by volume unless otherwise specified.

Example 1

8 liters of methane which have been led over mercury which has been brought to the boiling point are passed per hour through an internally tinned tube of V2A-steel, that is, a steel containing 7.5-9 parts of nickel, 15-17 parts of chromium and the balance of iron with minor amounts of carbon having an internal diameter of 15 millimeters which is heated to from 1000° to 1050° C. for 60 centimeters of its length. After separating the mercury behind the reaction chamber, a yellow brown mist forms which when further cooled yields a liquid condensate boiling up to 250° C. and consisting mainly of aromatic hydrocarbons. About 10 per cent or more of the methane is thus converted into liquid hydrocarbons.

The process may be carried out in a cycle by charging the residual gas after separating the reaction products and after lading it with mercury vapor through the reaction chamber again. Several reaction chambers arranged one behind another may also be employed. No formation of carbon black or other deposition of carbon can be detected even after working for long periods of time.

Example 2

35 liters of ethylene which has been laden with mercury vapor by passage over boiling mercury

are led per hour through an internally tinned tube of V2A-steel having an internal diameter of 18 millimeters and a length of about 60 centimeters and heated externally to about 725° C. The reaction product is a condensate which boils above 40° C. 92 per cent of it boils below 180° C. and it consists mainly of aromatic compounds of low boiling point. 22.4 per cent by weight of the ethylene employed is converted. Of the ethylene used up, 31.4 per cent by weight is converted into propylene, butylene and butadiene (the latter of which is isolated as the tetrabromide) and 42.5 per cent by weight is converted into the said liquid condensate.

15

Example 3

About 23.3 liters of a gas having the composition butane 0.7 per cent, propane 65.3 per cent, ethane 22.2 per cent, butylene 0.3 per cent, propylene 8.7 per cent and ethylene 2.8 per cent which have been laden with cadmium vapor are led per hour through a similar tube to that described in Example 2 which has been heated to from 750° to 775° C.

20

The reaction product consists of about 46 liters of a gas containing 4.5 per cent of propylene, buty-

lene and a little butadiene, 25.5 per cent of ethylene, 21.2 per cent of hydrogen and 48.9 per cent of methane and 5 grams of a condensate boiling above 40° C. having a composition similar to that described in Example 2 of which 70 per cent by weight boils below 200° C.

12.5 per cent by weight of propylene, butylene and a little butadiene, 35.2 per cent by weight of ethylene, 12.5 per cent by weight of liquid hydrocarbons, 37.8 per cent by weight of methane and 2.0 per cent by weight of hydrogen are obtained from the gas employed.

What we claim is:—

In the conversion of a normally gaseous hydrocarbon selected from the paraffinic and olefinic series into liquid hydrocarbons by heat treatment at a temperature, between 400 and 1100° C., sufficient for carrying into effect this conversion, the steps of charging the said gaseous hydrocarbon with up to about 2% by volume of mercury vapor at a temperature which lies above the melting point of mercury but below the said conversion temperature, and then heating the said gaseous hydrocarbon to the said conversion temperature.
